DRIVING MECHANISM FOR FLEXIBLE SHAFTS

Michael J. Sullivan, Springfield, Ohio

Application March 20, 1941, Serial No. 384,382

25 Claims.

(Cl. 242—54)

My invention relates to improvements in sewer cleaners, with particular reference to apparatus or machines employed in operating the flexible shaft or wire cable which carries the cutter or cleaning implement by which the obstruction is cut away or loosened from the sides of the sewer, an example of cutting implement forming the subject matter of my prior Patent No. 2,169,543, dated August 15, 1939.

In cleaning out obstructions in sewer pipes or drains it is customary to use a wire cable or flexible shaft, commonly known as a snake, and in some instances the wire cable is of considerable length necessitating the use of a reel and mechanism in association therewith for not only paying out the wire cable and rewinding it, but also for rotating the cable or flexible shaft in operating the implement employed for dislodging or removing the obstruction. In apparatus of this general character, for operating the cutter, it is usual to mount the reel in a supporting frame in such manner as to provide for revolving it laterally to rotate that portion of the wire cable extending beyond the apparatus, in addition to providing means for reeling and unreeling the wire cable, and the mechanism usually includes an electric motor for the operation thereof.

With this general construction of apparatus in mind my invention contemplates certain improvements that will not only facilitate the several operations but also perform the duties in a more competent and effective manner; that is, provide a construction of apparatus by means of which the wire cable or flexible shaft can be more easily and conveniently handled in performing the work required.

With this principal object in view my invention consists in the particular construction and combination of parts constituting the apparatus, as hereinafter fully described and more specifically set forth in the appended claims.

In the drawings:

Figure 1 is a side elevation of the apparatus constructed in accordance with my invention, the revolving reel carrying frame being shown in horizontal position.

Fig. 2 is a plan view with the reel carrying frame turned to bring the winding and unwinding mechanism uppermost.

Fig. 3 is an end view of the apparatus.

Fig. 4 is an enlarged detail plan view of the mechanism for revolving the reel carrying frame and for winding and unwinding the wire cable.

Fig. 5 is a detail view of one of the levers for engaging and disengaging the clutches connect-

ing the motor driven wheel to the driving shafts.

Fig. 6 is a vertical sectional view through the parts constituting the driving mechanism.

Figs. 7, 8, and 9 are views of auxiliary hollow shafts mounted on the main shaft, with the parts fixedly secured to each respectively.

Fig. 10 is a sectional view showing the manner of connecting one of the driving pinions to an auxiliary hollow shaft or sleeve.

10 Fig. 11 is a sectional view on the line 11—11 of Fig. 4.

Fig. 12 is a detail view of a friction-wheel forming part of the wire cable winding mechanism.

15 Figs. 13 and 14 are detail views to illustrate the construction of the wheel for directing the wire cable to the hollow main shaft through which said wire cable is led from the apparatus, and

Fig. 15 is a sectional view on the line 15—15 of Fig. 2.

20 The mechanism for carrying out the different functions of apparatus constructed in accordance with my invention is mounted in a supporting frame consisting of tubular bars 20, 20 of U-shape formation connected at their ends to shaft-bearings 21, 22 located at opposite ends of the apparatus and from which said U-shape bars diverge, with the horizontal bars resting on the ground, and for supporting the electric motor, 23, in association with the apparatus crosspieces 24, 24

25 are bolted on the horizontal members of the supporting frame at one end thereof, as shown in the drawings. Within the upper part of this supporting frame is mounted a rectangular reel carrying frame 25, made up of spaced apart

30 parallel channel bars 26, 26 connected at their ends by crosspieces 27 and 28, and so that this reel carrying frame may revolve laterally for turning the wire cable as hereinafter explained, the crosspiece 27 is provided with a stub shaft

35 29 journaled in the aforementioned bearing 21, while the crosspiece 28 is fixed to a hollow shaft 30 (see Fig. 6) extending therefrom and journaled in bearing 22 at the other end of the supporting frame.

40 45 Reel 31, on which the wire cable, 32, is wound, is mounted in the revoluble frame 25 near one end thereof, the shaft 33 of said reel being journaled in bearings 34, 34 bolted to the channel bars forming the side pieces of said frame, and for

45 50 rotating the shaft to wind the wire cable on the reel a ratchet wheel 35 keyed thereon is engaged by a pawl 36 pivoted to the inner side of a sprocket wheel 37 loosely mounted on the outer end of the shaft, said sprocket wheel being turned

55 by a sprocket chain 38 driven in the manner here-

inafter described. The cable passing from the reel is led from the apparatus through a hollow stationary main shaft 39 on which is journaled a crosspiece 40 of the revolute reel frame, said crosspiece being located intermediate the ends of the frame and the shaft extends therefrom through the rotatable hollow shaft 30—in the bearings 28 and 22—to beyond the outer end of the supporting frame where it is firmly supported by an inverted V-shape brace-bar 41 secured at its ends to brackets 42 projecting from the tubular bars of the main supporting frame and braced by rods 43. The main shaft is rigidly secured to this brace bar by means of a set screw 41a extending through the upper end of the brace into a hole or depression in the main shaft.

For revolving the reel carrying frame, and for rotating the reel through the medium of the sprocket chain, a large belt wheel 44 is loosely mounted on the hollow shaft 30 and driven from the electric motor by belt 45 passing around a small pulley 46 on the shaft of the motor and tightened by an idle pulley 47 supported at the outer end of an adjustable bracket-arm 48 belted to one of the diverging members of the brace-bar 41 supporting the outer end of the main shaft.

The reel carrying frame is revolved by connecting the belt wheel directly to the hollow shaft 30 extending from said frame through the bearing 22, the connection being effected by a clutch member 49 on the inner side of the hub of the belt wheel engaging a companion clutch member 50 keyed to the shaft—the shifting of the belt wheel being provided for by a lever 51 pivoted to plate 52 extending from the supporting frame and having a yoke 53 with rollers 54 engaging a circumferential groove 55 in the hub at the inner side of the clutch member. The belt wheel also operates the sprocket chain to rotate the reel for winding and unwinding the wire cable thereon, and for this purpose a rotatable sleeve 56 extends through the hollow shaft 30 for the operation of a bevel pinion 57 in gear with a large bevel wheel 58 shaft 59 of which is mounted in a bearing in one of the channel bars 26 and extends beyond the same to receive a small sprocket wheel 60 over which the sprocket chain passes to the larger sprocket wheel 37 on the reel shaft. For connecting the belt wheel to the rotatable sleeve the latter is provided at its outer end with a clutch member 61 adapted to be engaged by a clutch member 62 on the hub of the belt wheel at the opposite side thereof from the clutch member 49, and for connecting the rotatable sleeve to bevel pinion 57 the sleeve is provided at its enlarged inner end with a circumferential groove 63 (Fig. 10) and hole 64 in the bottom thereof for detachable engagement of a pin 65 carried by the pinion, being held out of engagement with the hole by a cross rod 66 at the outer end thereof resting on the outer end of a projection 67 through which the pin projects, and engaged by turning the pin so that the cross rod will enter opposite recesses 68. The pinion is loosely mounted on a sleeve 69 which is employed for operating a clutch-sleeve 70 slidable on the main shaft and having a clutch member 71 at one end adapted to engage a companion clutch member 72 on said pinion, with a clutch member 73 at its other end adapted to engage a companion clutch member 74 on a bevel pinion 75 loosely mounted on the main shaft and in mesh with the aforementioned bevel wheel 58, said clutch-sleeve being connected to slide on the main shaft by pin 76 engaging slot 77. Furthermore, bevel pinion 75 is adapted to be held in con-

nection with the reel carrying frame by means of a pin 78 slidable in the crosspiece 40, in addition to being held stationary, when desired, by engagement of the clutch-sleeve carried by the main shaft.

The slidable sleeve 69, hereinbefore referred to, is operated by a lever 79 supported in a bracket 80 bolted to and extending from the brace 41, said lever being similar in construction to that employed for shifting the belt wheel, the friction rollers engaging a circumferential groove 81 in a collar 82 fixed to the outer end of said sleeve, and as will be seen by reference to Sheet 3 of the drawings the sleeve 69 has slidable movement directly on the shaft 39 (Fig. 7), sleeve 56 is rotatable on said sleeve (Fig. 8), and shaft 30, carrying the driving belt wheel, is rotatable on sleeve 56—the sleeves being located within the outer shaft 30 and the assembly mounted on the stationary shaft through which the wire cable passes.

To guide the wire cable or flexible shaft from the reel to the inner end of the hollow main shaft, and for other purposes hereinabove explained, I provide a guide-wheel 83, which is interposed between the reel and inner end of the shaft, said wheel being somewhat in the nature of a grooved pulley, but instead of having a plain bottom to the groove around the circumference there are a series of teeth 84 at a pitch corresponding to that of the helices of the wire cable forming the flexible shaft, and in order that this guide wheel may change its position for properly leading the cable it is mounted on a supporting shaft 85 in a particular manner. In this instance the shaft is of such diameter as to provide for a reduced portion 86 and permit rocking movement of a collar 87 on which the wheel is mounted and which is connected to the shaft by diametrically opposite pins 88, lateral shifting movement of the wheel on an axis perpendicular to the shaft being provided for by pins 89 disposed at right angles to the pins 88 and which connect the body of the wheel to the collar. By this arrangement the guide wheel may assume different positions as the cable is unwound from the reel and wound thereon, the extent of the shifting and rocking movement depending on the width of the reel, and for feeding the wire cable the shaft 85 journaled in bearings 90, 90 bolted on the channel bars 26 of the reel carrying frame is extended at one side of said frame to receive a sprocket wheel 91 over which the sprocket chain 38 passes and with which it is held in engagement by an adjustable sprocket wheel 92, the latter being supported in a bracket 93 having a slot 94 through which the stub shaft 95 passes. The wire cable is kept in contact with the guiding wheel by means of a roller 96 adjoining the periphery thereof, said roller being journaled at its ends in bearings 97 attached to plates 98 bolted to the side pieces or channel bars of the reel carrying frame, with expansion springs 99 interposed between the bearings and plates for yieldingly supporting the roller in contact with the wire cable, as illustrated in Fig. 11 of the drawings. The circumference of this roller is provided with spiral ribs 100 pitched to correspond with the teeth in the groove of the wheel, and said roller cooperates with the wheel as the wire cable passes between them to the inner end of the hollow shaft 39. I also provide a friction clutch associated with the guide-wheel 83 and mounted on the outer end of shaft 85 for driving connection between sprocket wheel 91 and said shaft. This friction clutch consists of a split wheel 101 carrying the sprocket wheel

and loosely mounted on the shaft to work within the rim of an auxiliary wheel 102 keyed to the outer end of said shaft, whereby turning of the shaft by the sprocket wheel is effected by frictional engagement of the split wheel with wheel 102. The split wheel is expanded against the inner side of the rim of wheel 102 by a spring actuated pawl 103 pivoted on pin 104 extending from the hub and engaging an escapement wheel 105 fixed to one of the bearings 90 to operate a cam 106 through the medium of a bent rod 108. The cam turns between cooperating lugs 107, 107 at adjoining ends of the split rim of the wheel and the bent rod carrying the same works in a groove in the hub with an extension through a hole in the sprocket wheel for connection to one member of the pawl, the outer end of the other member of said pawl riding over the teeth of the escapement wheel to provide the required movement to operate the cam. It will be understood that the turning of the sprocket wheel and split wheel by the sprocket chain in that direction to pay out the wire cable will operate the pawl, bent rod and cam to expand the split wheel against the inner side of the rim of wheel 102 keyed to the shaft whereby the shaft is turned by frictional engagement of the wheels. When the sprocket wheel is turned to the opposite direction—in winding the wire cable on the reel—the pawl will ride freely over the teeth of the escapement wheel without operating the cam.

In addition to the mechanism hereinbefore described I provide a brake device which is applied against one side of the reel, and is in the form of a brake-shoe 111 at the inner end of a rod 112 threaded through a fixture 113 bolted to one of the channel bars forming the side pieces of the reel carrying frame. Furthermore, in order to connect the reel carrying frame directly to the supporting frame a pin 116 is passed through an opening therefor in the bearing 28 to engage a hole in the bearing 22, as shown in Fig. 6 of the drawings, and for wheeling the apparatus a pair of ground wheels 109, 109 is provided at the front of the apparatus, where the motor is located, said wheels being supported by a shaft 111 extending between the brackets 42, 42 on the tubular bars of the main supporting frame.

As some of the elements of the transmission gear are located beyond one side of the laterally revoluble reel carrying frame the weight of these elements is balanced at the other side of the frame by means of a counterbalancing weight 115 bolted to channel bar 26, and augmented by weight 114 spaced therefrom and located nearer the reel.

In winding the wire cable on to the reel to prepare the apparatus for doing the work for which it is designed, pin 65 is dropped into hole 64 for connecting pinion 57 to rotatable sleeve 56, and pin 78 is disconnected from the crosspiece 40 of the reel carrying frame to permit pinion 75 to run loosely on the main shaft—clutch-sleeve 70 being in an intermediate or neutral position. The mechanism is now ready for winding the wire cable on to the reel, and this operation is accomplished by starting the motor and shifting the belt-wheel by lever 51 to engage clutch 61—62 for rotating sleeve 56 and gearing driven by pinion 57 to drive the sprocket chain connected to sprocket wheel 31, the latter turning the shaft of the reel by engagement of pawl 36 with ratchet wheel 35. As the wire cable is wound on the reel guide wheel 83 runs freely and shifts auto-

matically to lead the cable from the inner end of the hollow main shaft to the reel for orderly arrangement thereon, in this instance free movement of the guide wheel taking place by reason of the pawl 103 running loosely over the ratchet teeth of wheel 105. During this operation the reel carrying frame is held stationary by pin 16, and after the wire cable is wound on to the reel, leaving an end projecting beyond the apparatus, any type of cleaning device or implement—as the cutter disclosed in my prior patent hereinbefore referred to—is attached to the outer end of the wire cable putting the apparatus in condition for operation in cleaning out a sewer. The mechanism is also arranged in this manner when it is desired to pull the wire cable and cutter out of the sewer, or to loosen the cutter should it become stuck, it being understood that in withdrawing the wire cable by this arrangement the cutter-head does not rotate.

To prepare the apparatus for turning the reel carrying frame to rotate the wire cable and cutter for the purpose of dislodging an obstruction from the sewer or drain pipe, the belt wheel is first put in neutral position, pin 116 is removed to disconnect the reel carrying frame from the supporting frame, and pin 65 withdrawn from the hole 64 so that pinion 57 of the transmission gear will turn freely on sleeve 69—clutch sleeve 70 being in neutral position and pin 78 withdrawn from pinion 75. Now by connecting clutch 49—50 to rotatable sleeve 30 the motor will revolve the reel carrying frame to which said sleeve is attached so as to rotate the wire cable without moving it in or out—such movement being controlled by the operation of lever 79 to shift clutch sleeve 70 into engagement with either one of the pinions 57 or 75, according to the direction the wire cable is to be moved. That is, the lever is operated to pay out the wire cable from the reel during the operation of the reel carrying frame by shifting the clutch sleeve to engage clutch 73—74 for holding pinion 75 to shaft 39 to operate the transmission gear, including the sprocket chain, while pinion 57 runs loosely on the inner end of sleeve 69. On the other hand, when it is desired to draw the wire cable outwardly in the sewer pipe to a more or less extent the clutch sleeve is shifted to engage clutch 71—72 thereby holding pinion 57 and allowing pinion 75 to run loosely for reversing the operation of the transmission gear and sprocket chain during the revoluble movement of the reel carrying frame. Thus the shifting of clutch sleeve 70 provides for quickly controlling the operation of the cutter in those instances where a stubborn obstruction is being dislodged from the sewer pipe, as the movement of the wire cable backward and forward can be accomplished to the fraction of an inch. When the wire cable is being drawn in pawl 36 engages ratchet wheel 35 to turn the reel—guide wheel 83 then serving merely to lead the cable to the reel—and when the wire cable is being payed out by reversing the operation of the transmission gear, as hereinbefore described, pawl 36 runs loosely over ratchet wheel 35 and the friction clutch comes into action for drawing the wire cable from the drum through the medium of said friction clutch which controls the turning of the guide wheel 83 by the sprocket wheel 31. The friction clutch works the same with a small amount of wire cable on the reel as it does with a full reel; that is to say, it is automatic and very

sensitive, for the reason it readily responds to the reversing movement of the transmission gear and sprocket chain, and in winding out the wire cable by guide wheel 83 the brake 111 presses against the side of the drum to retard its rotation.

From the foregoing description of the construction and operation of the apparatus it will be apparent that the mechanism provides for operating a wire cable or flexible shaft wound on a reel to not only feed out the cable and rotate the implement for cleaning out obstructions in the sewer pipe, but greatly facilitates the operation, with particular reference to controlling the operation of the cutter in cutting through a stubborn obstruction.

The apparatus is conveniently moved from one location to another by lifting that end of the supporting frame opposite the ground wheels so as to tilt the apparatus for supporting the same on said ground wheels, and the construction of the supporting frame is such that it will rigidly support the apparatus during the operation thereof as the tubular frame bars rest firmly on the ground.

It will be apparent that changes may be made in respect to some parts of the mechanism employed for carrying out my invention, and therefore I desire to reserve the right to obvious modifications within the spirit and scope of the appended claims.

I claim:

1. An apparatus for paying out a flexible shaft or wire cable from a reel and for rotating said cable, comprising a supporting frame having shaft bearings, a reel carrying frame journaled in the supporting frame for revoluble movement laterally, a shaft journaled in said frame and on which the reel is mounted, a hollow shaft fixed to the supporting frame to form the journal on which the outer end of the reel carrying frame revolves and through which the wire cable passes, a hollow shaft surrounding the fixed shaft and rotatable thereon, said rotatable shaft being connected to the reel carrying frame, and means for rotating said shaft; together with transmission gear between the rotatable shaft and shaft carrying the reel on which the wire cable is wound.

2. An apparatus for paying out a flexible shaft or wire cable from a reel and for rotating said cable, comprising a supporting frame, a reel carrying frame journaled in the supporting frame for revoluble movement laterally and in which the reel is rotatably mounted, a hollow shaft fixed to the supporting frame to form the journal on which the outer end of the reel carrying frame revolves and through which the wire cable passes, a rotatable shaft surrounding the fixed shaft and connected at its inner end to the reel carrying frame for turning the latter, a driving wheel loosely mounted on said shaft and connected thereto by a clutch to revolve the reel carrying frame, transmission gear between said driving wheel and reel on which the wire cable is wound, and a clutch for connecting the wheel to the transmission gear.

3. An apparatus in accordance with claim 2 and including means carried by the revoluble reel carrying frame and operated by the transmission gear for paying out the wire cable from the reel.

4. An apparatus for paying out a flexible shaft or wire cable from a reel and for rotating said cable, comprising a supporting frame, a reel carrying frame journaled in the supporting frame

for revoluble movement laterally and in which the reel is mounted, a hollow shaft fixed to the supporting frame to form the journal on which the outer end of the reel carrying frame revolves and through which the wire cable passes, a rotatable shaft surrounding the fixed shaft and connected at its inner end to the reel carrying frame, a driving wheel for rotating said shaft to revolve the reel carrying frame, transmission gear between the driving wheel and reel on which the cable is wound, and clutches for connecting the driving wheel to the rotatable shaft and transmission gear respectively.

5. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a rotatable shaft surrounding the fixed shaft and connected at its inner end to the reel carrying frame, a driving wheel for rotating said shaft to revolve the reel carrying frame, transmission gear between the driving wheel and reel on which the cable is wound, and clutches for connecting the driving wheel to the rotatable shaft and transmission gear respectively; together with means carried by the revoluble reel carrying frame and operated thereby for paying out the wire cable from the reel.

6. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively.

7. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively; together with means carried by the reel carrying frame and operated by the transmission gear for paying out the wire cable from the reel.

8. An apparatus for paying out a flexible shaft

or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a rotatable shaft surrounding the fixed shaft and connected at its inner end to the reel carrying frame, a driving wheel for rotating said shaft to revolve the reel carrying frame, transmission gear between the driving wheel and reel on which the cable is wound, said transmission gear including ratchet and pawl mechanism between the shaft of the reel and an element of the transmission gear for turning the reel to wind the wire cable thereon, and clutches for connecting the driving wheel to the rotatable shaft and transmission gear respectively.

9. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a rotatable shaft surrounding the fixed shaft and connected at its inner end to the reel carrying frame, a driving wheel for rotating said shaft to revolve the reel carrying frame, transmission gear between the driving wheel and reel on which the cable is wound, said transmission gear including ratchet and pawl mechanism between the shaft of the reel and an element of the transmission gear for turning the reel to wind the wire cable thereon, and clutches for connecting the driving wheel to the rotatable shaft and transmission gear respectively; together with means carried by the reel frame and operated by the transmission gear for paying out the wire cable from the reel.

10. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively; together with means carried by the reel carrying frame and operated by the transmission gear for paying out the wire cable from the reel, said means including a grooved wheel over which the wire cable passes from the reel to the hollow shaft, and a friction clutch on the shaft of the wheel operated by the transmission gear for retarding the rotation of the wheel.

11. An apparatus for paying out a flexible shaft or wire cable from a reel and for rotating said cable, comprising a supporting frame, a reel carrying frame journaled in the supporting frame

for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively; together with means carried by the reel carrying frame and operated by the transmission gear for paying out the wire cable from the reel, said means including a wheel having a circumferential groove with teeth in the bottom thereof pitched to correspond with the pitch of the helices of the wire cable, and a friction clutch connecting the shaft of the wheel to the transmission gear.

12. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively; together with means carried by the reel carrying frame and operated by the transmission gear for paying out the wire cable from the reel, said means including a wheel having a circumferential groove with teeth in the bottom thereof pitched to correspond with the pitch of the helices of the wire cable, an idle roller bearing against the wire cable adjoining said wheel and having teeth pitched to correspond with the teeth on the wheel, and a friction clutch connecting the shaft of the wheel to the transmission gear.

13. An apparatus for paying out a flexible shaft or wire cable from a reel and for rotating said cable, comprising a supporting frame, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft surrounding the fixed shaft and connected at its inner end to the reel carrying frame, a driving wheel loosely mounted on the rotatable shaft, transmission gear between the driving wheel and reel for winding and unwinding the wire cable thereon, clutch members at opposite sides of the hub of the driving wheel, and companion clutch members for connecting the driving wheel to the rotatable shaft and transmission gear respectively; together with means carried by the reel carrying frame and operated by the transmission gear for paying out the wire

cable from the reel, said means including a wheel connected to a shaft to have rocking and shifting movement for guiding the wire cable from the reel to the inner end of the hollow shaft through which it passes from the apparatus, and a friction clutch connecting the wheel shaft to the transmission gear.

14. The combination with an apparatus for paying out a flexible shaft or wire cable from a reel and for rotating said cable, including a supporting frame, a reel carrying frame journaled therein for revoluble movement laterally and in which the reel is mounted, and a hollow shaft through which the wire cable passes from the apparatus, of means for feeding the cable from the reel to the hollow shaft including a wheel mounted on a shaft supported in the reel carrying frame, means connecting the wheel to the shaft to provide for rocking and shifting movement of the wheel to lead the cable from the reel, and means for turning the wheel.

15. The combination with an apparatus for paying out a flexible shaft or wire cable from a reel and for rotating said cable, including a supporting frame, a reel carrying frame journaled therein for revoluble movement laterally and in which the reel is mounted, and a hollow shaft through which the wire cable passes from the apparatus, of means for feeding the cable from the reel to the hollow shaft including a wheel having a circumferential groove with teeth in the bottom of the groove pitched to correspond with the pitch of the helices of the wire cable, means connecting the wheel to the shaft to provide for rocking and shifting movement of the wheel to lead the cable from the reel to the hollow shaft, an idle roller bearing against the wire cable adjoining the periphery of the wheel and having longitudinal teeth pitched to correspond with the teeth in the groove of the wheel, means for turning the shaft on which the wheel is mounted, and a friction clutch for retarding the turning of the shaft.

16. The combination with an apparatus for paying out a flexible shaft or wire cable from a reel and for rotating said cable, including a supporting frame, a reel carrying frame journaled therein for revoluble movement laterally and in which the reel is mounted, and a hollow shaft through which the wire cable passes from the apparatus, of means for feeding the cable from the reel to the hollow shaft including a wheel mounted on a shaft, a collar interposed between the wheel and shaft and connected to the shaft by oppositely disposed pins for rocking movement of the collar on the shaft, and oppositely disposed pins connecting the wheel to the collar at right angles to the aforementioned pins for lateral shifting movement of the wheel, said wheel having a circumferential groove with teeth pitched to correspond with the pitch of the helices of the wire cable, and means for turning the shaft.

17. The combination with an apparatus for paying out a flexible shaft or wire cable from a reel and for rotating said cable, including a supporting frame, a reel carrying frame journaled therein for revoluble movement laterally and in which the reel is mounted, and a hollow shaft through which the wire cable passes from the apparatus, of means for feeding the cable from the reel to the hollow shaft including a wheel mounted on a shaft, a collar interposed between the wheel and shaft and connected to the shaft by oppositely disposed pins for rocking movement of the collar on the shaft, and oppositely disposed

pins connecting the wheel to the collar at right angles to the aforementioned pins for lateral shifting movement of the wheel, said wheel having a circumferential groove with teeth pitched to correspond with the pitch of the helices of the wire cable, means for turning the shaft, and a friction clutch for retarding the turning of the shaft.

18. The combination with an apparatus for paying out a flexible shaft or wire cable from a reel and for rotating said cable, including a supporting frame, a reel carrying frame journaled therein for revoluble movement laterally and in which the reel is mounted, and a hollow shaft through which the wire cable passes from the apparatus, of means for feeding the cable from the reel to the hollow shaft including a wheel mounted on the shaft, a collar interposed between the wheel and shaft and connected to the shaft by oppositely disposed pins for rocking movement of the collar on the shaft, and oppositely disposed pins connecting the wheel to the collar at right angles to the aforementioned pins for lateral shifting movement of the wheel, said wheel having a circumferential groove with teeth pitched to correspond with the pitch of the helices of the wire cable, an idle roller having longitudinal teeth pitched to correspond with the pitch of the teeth on the wheel, and means for turning the shaft of the wheel including a friction clutch for retarding the rotation of the wheel.

19. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, and means for operating the clutches.

20. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, and means for operating the clutches, one of the gears being detachably connected to the reel carrying frame.

21. An apparatus for paying out a flexible shaft or wire cable from a reel and for rotating said cable, comprising a supporting frame hav-

ing shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft, a rotatable sleeve interposed between the stationary and rotary shafts and connected to the driving wheel by a clutch, transmission gear between the inner end of the sleeve and reel on which the wire cable is mounted, a clutch connecting the driving wheel to the sleeve, and means for operating the clutches, said transmission gear including a bevel wheel and bevel pinions at opposite sides thereof mounted in the reel carrying frame with one of the pinions detachably connected to said reel carrying frame for operating the transmission gear by the turning movement of the reel carrying frame.

22. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, and means for operating the clutches, said transmission gear including a bevel wheel and bevel pinions at opposite sides thereof mounted in the reel carrying frame with one of the pinions detachably connected to said reel carrying frame for operating the transmission gear by the turning movement of the reel carrying frame; together with a wheel for guiding the wire cable from the reel to the shaft through which it passes from the apparatus, said wheel being operated by the transmission gear, a roller cooperating with the wheel, and a friction clutch for retarding the rotation of the wheel.

23. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, a

clutch connecting the driving wheel to the sleeve, and means for operating the clutches, said transmission gear including a bevel wheel and bevel pinions at opposite sides thereof mounted in the reel carrying frame with one of the pinions detachably connected to said reel carrying frame for operating the transmission gear by the turning movement of the reel carrying frame; together with a wheel for guiding the wire cable from the reel to the shaft through which it passes from the apparatus, said wheel being operated by the transmission gear and having circumferential teeth for engagement with the wire cable, a roller cooperating with the wheel and having corresponding longitudinal teeth or ribs, and a friction clutch for retarding the rotation of the wheel.

24. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, a clutch connecting the driving wheel to the sleeve, and means for operating the clutches, said transmission gear including a bevel wheel and bevel pinions at opposite sides thereof mounted in the reel carrying frame with one of the pinions detachably connected to said reel carrying frame and the other pinion loosely mounted adjoining the inner end of the rotatable sleeve, means for detachably connecting the last mentioned pinion to the rotatable sleeve, a clutch member slidably on the fixed shaft and interposed between the bevel pinions for engagement with either one of said pinions, a longitudinally movable sleeve on the stationary shaft between the rotatable sleeve and stationary shaft, and means for operating said longitudinally movable sleeve.

25. An apparatus for paying out a flexible shaft or wire cable from a reel and for rotating said cable, comprising a supporting frame having shaft bearings at the ends thereof, a reel carrying frame journaled in the supporting frame for revoluble movement laterally and in which the reel is mounted, a hollow shaft fixed to the supporting frame to form the journal on which the outer end of the reel carrying frame revolves and through which the wire cable passes, a hollow shaft connected at its inner end to the reel carrying frame and surrounding the stationary shaft for rotation thereon, a driving wheel loosely mounted on the rotatable shaft and connected thereto by a clutch, a rotatable sleeve interposed between the stationary and rotary shafts and connected to the driving wheel by a clutch, transmission gear between the inner end of the sleeve and reel on which the wire cable is mounted, and means for operating the clutches, said transmission gear including a bevel wheel and bevel pinions at opposite sides thereof mounted in the reel carrying frame with one of the pinions detachably connected to said reel carrying frame and the other

er pinion loosely mounted adjoining the inner end of the rotatable sleeve, means for detachably connecting the last mentioned pinion to the rotatable sleeve, a clutch member slideable on the fixed shaft and interposed between the bevel pinions for engagement with either one of said pinions, a longitudinally movable sleeve on the stationary shaft between the rotatable sleeve and stationary shaft,

and means for operating said longitudinally movable sleeve; together with a wire cable guiding wheel between the reel and hollow shaft through which said cable passes from the apparatus, an idle roller cooperating with the guiding wheel, and a friction clutch retarding the rotation of the guiding wheel.

MICHAEL J. SULLIVAN.
